UNITED STATES PATENT OFFICE.

WILLIAM P. ORDWAY, OF BOSTON, MASSACHUSETTS.

DESIGN FOR A CARD-CASE ATTACHMENT.

SPECIFICATION forming part of Design No. 28,053, dated December 14, 1897.

Application filed October 29, 1897. Serial No. 656,844. Term of patent 14 years.

To all whom it may concern:

Be it known that I, WILLIAM P. ORDWAY, a citizen of the United States, residing at Boston, in the county of Suffolk and State of Massachusetts, have invented and produced a new and original Design for an Attachment to Card-Cases, of which the following is a specification, reference being had to the accompanying drawing, forming a part thereof, in which is shown a perspective view of an attachment to card-cases embodying the features of my design.

The design relates particularly to devices to be used in connection with a card-case in the game of duplicate whist, the object of the invention being to provide for the several hands in the game being kept separate while contained in the same receptacle and likewise to provide for the ready removal from or the introduction into the case of any particular hand.

The design consists in arched strands A, B, and C, spaced one from the other, the termi-

nals of the outer strands, which are diagonally opposite, being formed into hooks a^1 , a^2 , a^3 , whose lower ends are carried in direction of the intermediate strands. Where the strands A and B connect a hook a^1 is shown, provided with twin shanks, and where the strands B and C connect a corresponding hook a^3 is produced. All the hooks rise above the end portions of the strands, and the return portions of the hooks extend downward to a point near the actual terminals of said strands.

The leading feature of the design consists in the arched strands, the central strand whereof is more decidedly arched than the outer strands and extends at its apex above the apices of the outer strands.

I claim--

The design for an attachment to card-cases herein shown and described.

WILLIAM P. ORDWAY.
